UNITED STATES PATENT OFFICE.

FRANK B. HOWARD, OF NEW YORK, N. Y., ASSIGNOR TO LAFLIN & RAND POWDER COMPANY, OF NEW YORK, N. Y., A CORPORATION OF NEW YORK.

APPARATUS FOR MAKING CLOSED VESSELS FROM PULP.

SPECIFICATION forming part of Letters Patent No. 711,165, dated October 14, 1902.

Application filed January 16, 1902. Serial No. 90,026. (No model.)

To all whom it may concern:

Be it known that I, FRANK B. HOWARD, a citizen of the United States, and a resident of the borough of Manhattan, in the city and State of New York, have invented a new and useful Apparatus for Making Closed Vessels from Pulp, of which the following is a specification.

My invention relates to apparatus for making closed vessels from pulp, with the object in view of providing simple and effective means for expediting the manufacture of such articles without joint or seam.

My present invention relates more particularly to apparatus for carrying out what I am pleased to call the "vacuum process," in which the pulp is forced toward the wall of the mold by internal atmospheric pressure as the pressure is removed from the exterior wall of the mold by means of some suitable vacuum appliance—as, for example, an exhaust-pump.

A practical embodiment of my invention is represented in the accompanying drawings, in which—

Figure 1 is a view of the apparatus in longitudinal section, showing the position of the condensed pulp around the margin of the mold to form the wall of the closed vessel, and Fig. 2 is a transverse central section of the same.

The body of the mold is composed of longitudinal sections—in the present instance three longitudinal sections—each forming a third of the body, and these sections are denoted by *a*, *b*, and *c*. They are each formed hollow, the interior space of the section *a* being denoted by *a'*, that of *b* by *b'*, and that of *c* by *c'*. The inner wall of each section is provided with manifold perforations *d*, through which the spaces *a'*, *b'*, and *c'* communicate with the interior of the mold. The spaces *a'*, *b'*, *c'* also communicate with one another at the meeting edges of the sections, and the space *b'* is connected, by means of a pipe *e*, with a vacuum appliance of any well-known or approved form—such, for example, as an exhaust-pump. (Not shown.) The pipe *e* extends into the hollow through a trunnion *f*,

projecting from the mold-section *b* and having a rotary movement in a bearing *g*, fixed to a support *h*. The trunnion *f* is conveniently held in position by means of a set-screw *i*, which extends through the bearing *g* into an annular groove *j*, formed in the periphery of the trunnion *f*.

From the above it follows that when the exhaust is applied through the pipe *e* to the interior of the section *b* it will also affect the sections *a* and *c*, which are in communication with the section *b*.

The several sections *a*, *b*, and *c* are held in assembled adjustment by means of heads *k* and *l*, each provided with a shallow recess, that in the head *k* being denoted by *k'* and that in the head *l* by *l'*, for the purpose of receiving the opposite ends of the assembled sections *a*, *b*, and *c* when the heads are drawn toward each other. The heads are hinged at *m* to the section *b* of the mold, and a rod *n*, hinged to the section-head *l* at *n'* and arranged to swing at its free end into an open slot *k'* in the head *k*, has its screw-threaded free end provided with a thumb-nut *o* for the purpose of forcing the heads toward each other to lock the parts in assembled adjustment and for releasing the rod *n* to permit the heads to be swung apart when it is desired to remove the completed article.

The heads *k* and *l*, like the side sections of the mold, are made hollow, the space within the head *k* being denoted by *k''* and that within the head *l* by *l''*. The inner walls of the head, like the inner sides of the walls of the mold, are also perforated in order to establish communication between the spaces or chambers *k''* or *l''* and the interior of the mold. These spaces *k''* and *l''* are also in communication through pipes *p* and *p'* with the vacuum appliance with which the pipe *e* communicates, so that when the said vacuum appliance is operated it will simultaneously tend to produce a vacuum in both the heads, as well as the body, of the mold.

The head *k* is provided in the present instance centrally with an opening *k⁴* for the reception of a plug *q*, the latter being projected inwardly from the head *k* a sufficient

distance (the thickness of the wall of the vessel to be formed) to form the bung or filling hole of the manufactured article.

The plug *q* is provided with a vent *r*, in the 5 present instance formed in a supplemental plug *r'*, seated within the plug *q*, the said vent serving to supply the air-pressure to the interior of the mold when the vacuum appliance is in operation.

10 The entire interior of the mold is covered with a wire-gauze *s*.

The operation is as follows: The mold having been turned into position with its head *k* uppermost, as shown in Fig. 1, the plug *q* is 15 removed and the mold is supplied with its charge of pulp in a free-flowing state of suspension. The plug, with its vent *r*, is then inserted in position and the vacuum appliance set in operation to produce a vacuum 20 within the body and heads of the mold. This will cause a flow of the liquid pulp toward all of the walls of the mold and will cause the pulp itself to be deposited under atmospheric pressure, while the water escapes through 25 the perforations in the mold and through the pipes *e*, *p*, and *p'*. When the pulp has been deposited to a sufficient extent to form the wall of the vessel, the vacuum may be relieved and the mold turned in a position with 30 its head *k* downward to permit the removal of any remaining suspended pulp, and the mold may then be opened and the vessel removed for drying.

What I claim is—

1. An apparatus for manufacturing vessels 35 from pulp comprising a mold for the reception of the pulp in suspension the said mold being mounted to rock on its support the walls of the mold being hollow and in communication with the interior space of the mold 40 through manifold perforations and means for placing a vacuum appliance in communication with the interiors of the hollow walls of the mold for inducing a deposit of the pulp on the interior of the mold, substantially as set 45 forth.

2. Apparatus for forming closed vessels from pulp comprising a mold having its body and heads formed hollow, the interior of said hollow heads and body being in communication with the interior of the mold through manifold perforations, a vent extending from the exterior to the interior of the mold the said mold being mounted to rock on its support and means for placing a vacuum appliance 50 in communication with the interior heads and body of the mold for inducing the deposit of the pulp on the interior of the mold, substantially as set forth.

In testimony that I claim the foregoing as 60 my invention I have signed my name, in presence of two witnesses, this 2d day of January, 1902.

FRANK B. HOWARD.
